Patented Sept. 24, 1963

196,353

CARTRIDGE BELT

Gerald R. Chapin, Rte. 2, Box 326, Greeley, Colo.

Filed Mar. 18, 1963, Ser. No. 74,052

Term of patent 14 years

(Cl. D3—10)

FIG. 1 is a perspective view of a cartridge belt showing my new design;

FIG. 2 is a perspective view thereof as it appears from the side opposite that shown in FIG. 1; and

FIG. 3 is a cross-sectional view thereof taken on the line 3—3 of FIG. 2, and looking in the direction of the arrows.

I claim:

The ornamental design for a cartridge belt, as shown.
